UNITED STATES PATENT OFFICE.

FRANK ZEISBERGER AND WALTER SCOTT, OF LONDON, ENGLAND.

BOOT TREE AND LAST.

No. 817,949.

Specification of Letters Patent.

Patented April 17, 1906.

Application filed February 20, 1905. Serial No. 246,574.

To all whom it may concern:

Be it known that we, FRANK ZEISBERGER, waiter, and WALTER SCOTT, railway inspector, residing at 16 Fitzroy road, Primrose Hill, N. W., London, England, subjects of the King of Great Britain and Ireland, have invented certain new and useful Improvements in Boot Trees and Lasts, of which the following is a specification.

- 10 The object of this invention is to provide an improved last which may be adapted to boots and shoes of various shapes and sizes and which is capable of being collapsed and folded, so as to occupy only a small space.
- 15 For this purpose the improved last is formed of any suitable elastic material, such as india-rubber, so arranged or adapted as to form a hollow chamber of any desired shape or size into which is forced air under pressure
- 20 for the purpose of distending the same to the shape and size of the boot or shoe. In order to increase the strength of the said last and prevent the sides from being unduly forced or bulged outward by the internal pressure,
- 25 the said sides may be formed partly of leather, celluloid, or other solid pliable material, or the last may be made of cloth or other pliable or elastic material and the sides thereof be drawn into close contact with each
- 30 other and stitched together for a portion of their surfaces, so as to leave a space all round the last for the reception of the pneumatic elastic chamber. This chamber when distended conforms to the shape of the boot or shoe and prevents any pressure on the sides where they are connected together.

The upper end of the last terminates in a plate or cover, which may be formed of wood or other solid material, to which is fitted a self-closing air-valve for filling the chamber by means of an air-pump or inflator, and the bottom of the last may be formed of canvas, leather, cardboard, paper, or other suitable inner and outer soles stitched or cemented to the body or sides and to each other. We also prefer to strengthen the said sole by providing an extra sole or plate, which may be of similar material and is bent over or curved downward at its edges to bear upon

50 the inner sole and form a space between it

and the latter, and in order to clearly understand our invention, reference is had to the accompanying sheet of drawings, in which—

Figure 1 is a side elevation of the improved last in its distended form. Fig. 2 is a vertical section thereof, and Fig. 3 is a cross-section.

a is the body of the last, which may be formed of cloth or other pliable or elastic material, and *b* is the inner or elastic air chamber. As shown in the drawings, this chamber conforms to the shape of the boot when distended and is formed with an opening or space *c* to permit of the sides of the body *a* being stitched together in contact with each other, as shown at *d*, Fig. 3, the stitching being indicated by the dotted line *e* in Fig. 1

f is the solid top of the last, to which is fitted the air-valve nipple *g*, and *h h'* are respectively the inner and outer soles secured to the body *a*.

i is the extra sole or plate curved over its edges to bear upon the sole *h* and form a space *j* for the purpose of receiving the pressure from the air-chamber *b* and increasing the strength of the sole.

A self-closing valve is fitted to the nipple *g* and air is pumped in through the same to the chamber *b* after the last is placed within the boot until the said chamber is distended to the required degree.

To remove the last from the boot, the air is let out through the valve from the chamber *b*, so that the latter may be collapsed and the last be readily withdrawn from the boot.

This last is especially applicable for the use of travelers, as when deflated it can be readily folded up and packed into a very small space.

Having now fully described the nature of our said invention, what we claim, and desire to secure by Letters Patent, is—

The improved boot tree or last consisting of the combination of a pliable body forming the same, a pneumatic elastic chamber being closed in a space in said body formed by stitching together the central portion of the sides of the latter, an air-valve for inflating the said chamber in the space so formed

the shape and size of the boot or shoe, inner and outer soles, and an inner arch or hollow sole or plate, placed between the elastic chamber or body and the inner sole, for receiving the pressure caused by the inflation of the said chamber and for strengthening the outer sole, substantially as described.

In witness whereof we have hereunto our hands in the presence of two witnesses:

FRANK ZEISBERG
WALTER SCOTT.

Witnesses:

M. C. SMITH,
ALBERT JOHN BOYCE.
